CLAIM

The ornamental design for a food cooking tray for a cooking appliance, as shown and described.

DESCRIPTION

FIG. 1 is a perspective view taken from the front and left side thereof of a food cooking try for a cooking appliance showing my new design;
FIG. 2 is a top plan view thereof;
FIG. 3 is a bottom plan view thereof;
FIG. 4 is a right side elevational view thereof, with the left side elevational view being a mirror image; and,
FIG. 5 is a front elevational view thereof, with the rear elevational view being a mirror image.
